Primary Examiner — Eric Goodman*Assistant Examiner* — Christian P McLean(74) *Attorney, Agent, or Firm* — Knobbe, Martens, Olson & Bear LLP**CLAIM**

The ornamental design for a display screen or portion thereof with graphical user interface, as shown and described.

DESCRIPTION

FIG. 1 is a front view of a display screen or portion thereof with graphical user interface showing our new design; FIG. 2 is a front view of FIG. 1 shown in a different environment;

FIG. 3 is an enlarged front view of FIG. 1 shown removed from the environment; and,

FIG. 4 is an enlarged view of FIG. 1 shown removed from the environment.

The broken lines showing a display screen or portion thereof, text, and other elements form no part of the claimed design.
